UNITED STATES PATENT OFFICE.

GEORGE R. BENNETT, OF DENVER, COLORADO.

ROCK-DRILL.

1,183,846.

Specification of Letters Patent.

Patented May 23, 1916.

Application filed October 15, 1912. Serial No. 725,820.

To all whom it may concern:

Be it known that I, GEORGE R. BENNETT, a citizen of the United States of America, residing at Denver, in the county of Denver 5 and State of Colorado, have invented certain new and useful Improvements in Rock-Drills, of which the following is a specification.

My invention relates to improvements in 10 rock drills and its object resides in the provision of an engine of this class in the operation of which, a rapid succession of blows is effectively delivered upon a cutting tool by the coöperative actions of a mechanical 15 agent and a motive fluid such as air under compression.

An embodiment of my invention is illustrated in the accompanying drawings in the various views of which like parts are similarly 20 designated and in which,

Figure 1 represents a side elevation of the improved rock drill, Fig. 2 a longitudinal section of the same drawn to an enlarged scale with the parts in the position they occupy 25 when the reciprocating piston included in the construction, has reached the end of its forward stroke, Fig. 3 a similar view with the moving parts in their positions at the termination of the rearward movement 30 of the piston, and Fig. 4 a cross-section taken along the line 4—4, Fig. 2.

Referring to the drawings by numerals, 2 designates a cylindrical housing supported on a suitable base 3 and provided at its rear 35 end with a stuffing box 4 for the support and impervious guidance of the rod 5 of a reciprocating piston 6 which is slidably fitted in the housing. The latter has at its forward end an axially alined sleeve 7 for 40 the support of a cutting tool 8 whose shank projects into the interior of the housing to be driven forwardly by the impact of a reciprocating hammer as will hereinafter be described. The housing 2 has furthermore, 45 at its forward end a plurality of ports 9 for the admission of air under atmospheric pressure to its interior, and a conduit 10 connects an opening at its opposite end with a source of motive fluid such as air under compression. The rearward portion of the housing is, 50 internally, increased in diameter to receive an internally, longitudinally fluted bushing 12 which serves to provide a plurality of longitudinal channels 13 which, when the piston has reached the end of its rearward stroke, establish communication be-

tween the portions of the housing at opposite sides thereof.

The hammer 18 which in the operation of the drill impinges upon the end of the tool 60 8, is slidably fitted in the housing between the forward end thereof and the reciprocating piston to be actuated by the motive fluid which flows through the channels past the piston when the latter reaches the end of its rearward stroke. The piston 6 is provided with an internal valve chamber 14 which has an opening in the forward face thereof and which is in continuous communication with its opposite face by a plurality of passages 15. A check-valve 16 which is normally held against its seat by a coiled spring 17 is arranged to open for the escape of compressed air from the space between the hammer 18 and the piston, during forward 70 movement of the latter after the hammer has delivered a blow upon the tool at the forward end of the housing. The piston-rod 5 is connected at its protruding extremity with a mechanism of suitable construction 75 adapted to impart a reciprocating movement to the piston, as, for example, the crank disk 19 and the connecting rod 20 shown in Fig. 1 of the drawings.

In the operation of the rock drill, the portion of the housing between the rearward end thereof and the piston 6 may either be filled with compressed air, it may be placed in continuous communication with a source of motive fluid by means of the conduit 10, 80 or a check-valve 21 may be applied as is shown in Fig. 3, to interrupt the return-flow of fluid to the source of supply, when during rearward movement of the piston the air contained in the housing is over-compressed. Assuming that both the hammer 18 and the piston 6 are at the end of their forward movement in the position shown in Fig. 2, power is applied to the crank-shaft to draw the piston rearwardly. Inasmuch 85 as the hammer and the piston are closely fitted in the cylinder, the rearward movement of the piston will tend to create a partial vacuum between them with the result that the hammer is compelled to follow the piston in its rearward movement by pressure of the air admitted into the housing through the ports 9 at the forward end thereof. These corresponding movements of the two 90 reciprocating elements will continue until 100 the piston on reaching the end of its rearward stroke, uncovers the ends of the chan-

nels 13, when the compressed air contained in the rearward portion of the housing, escapes into the space between the piston and the hammer, to drive the latter forwardly 5 against the extremity of the drilling-tool 8. During the subsequent forward movement of the piston, the body of fluid by which the hammer was impelled, is forced past the check-valve 16, into the rearward portion of 10 the housing until the piston has again reached the end of its forward stroke when the above described operation is repeated.

Having thus described my invention, what I claim and desire to secure by Letters-Patent is:

1. The combination of a rear-end closed cylinder, the rear portion of the chamber of said cylinder being increased diametrically, said rear diametrically increased chamber 20 having a bushing provided with a plurality of longitudinal channels, a longitudinally movable tool arranged at the forward end of said cylinder, a piston arranged within the rearward end of said cylinder and having 25 a valve chamber in communication with its opposite end faces, a valve arranged in said chamber providing for a rearward flow of fluid therethrough, a second piston intermediate the first referred to piston and said 30 tool, said cylinder having air-inlet ports at its forward end and said longitudinal channels communicating with the space between

the pistons and the space at the rear of the first referred to piston when the latter piston reaches a predetermined point in its travel.

2. The combination of a rear end closed cylinder, the rear portion of the chamber of said cylinder being increased diametrically, said rear diametrical chamber having a 40 bushing provided with a plurality of longitudinal channels, a longitudinally movable tool arranged at the forward end of said cylinder, a piston arranged within the rearward end of said cylinder and having a spring-controlled valve arranged within a chamber thereof, said piston also having a plurality of passages communicating with said chamber and opening through the rear end of the piston, a second piston intermediate said tool and the first referred to piston, said cylinder having air-inlet ports at its forward end and said longitudinal channels communicating with the space between the pistons and the space at the rear of the first referred to piston when the latter piston reaches a predetermined point in its travel.

In testimony whereof I have affixed my signature in presence of two witnesses.

GEORGE R. BENNETT.
